United States Patent Office.

GEORGE H. SANBORN, OF BOSTON, MASSACHUSETTS.

Letters Patent No. 71,793, dated December 3, 1867.

MACHINE FOR CUTTING PAPER.

The Schedule referred to in these Letters Patent and making part of the same.

TO ALL WHOM IT MAY CONCERN:

Be it known that I, GEORGE H. SANBORN, of Boston, in the State of Massachusetts, have invented an improved Paper-Cutting Machine; and I do hereby declare the following to be a full and correct description of the same, reference being had to the accompanying drawings, in which—

Figure 1 is a perspective view of the machine complete.

Figure 2 is a diagram on a larger scale, illustrating the mode of operating the clutch by the hand-lever and treadle.

Figure 3 is a similar diagram, showing the automatic mechanism for operating the clutch.

The same letter indicates the same part wherever it occurs.

This invention relates to that class of paper-cutting machines in which the knife is hung on oscillating parallel bars, and gives a sliding or "draw" cut as it descends towards the table. It consists in a new mode of operating the knife; in the application of a movable index and graduated scale, to measure accurately the movements of the gauge; and in the arrangement of mechanism for imparting to the knife a more rapid motion on its upward than it has on its downward stroke, all as hereinafter more particularly set forth.

To enable others to make and use my improved cutting-machine, I will proceed to describe its construction and operation, referring to the drawings, by the letters of reference marked thereon.

A marks a stout frame of iron, to which the operative parts are attached. B is a winch attached to the pinion C, which meshes into the gear-wheel D on the end of the main shaft E. On shaft E is a small bevelled pinion, F, gearing into bevelled wheel G, on the front end of shaft H, which runs at right angles to the main shaft, towards the rear of the machine. On this shaft are the loose pinion I and the loose wheel K, both of which are so constructed as to engage with clutch L when its jaws are brought into contact with them. L is a double clutch, with jaws on both faces, made to fit corresponding jaws on the pinion I and wheel K. It traverses longitudinally on shaft H, and rotates with it, being attached to it by means of a groove sliding on a feather on the shaft. A groove on the periphery of the clutch receives a pin, d, attached to slide M, so that the longitudinal movement of that slide imparts a similar movement to the clutch, and causes it to engage either the pinion I or wheel K, according to the direction in which it is impelled by slide M. This slide has a reciprocating movement in the direction of its length, and can be operated either by the hand-lever N, the treadle S, or the rock-shaft S'. The lever N has its fulcrum at a, and is connected with slide M by link P and the pins b c. The treadle S is connected with the slide M by rod R and bent lever Q, the last having its fulcrum at g, and a fork in its upper end, which receives the pin e, projecting from M. Pins, h and i, connect the rod R to lever Q and treadle S. The treadle is pivoted to the frame A at l. The hand-lever N is used to throw the clutch into gear to start the machine. The treadle is intended to stop the machine at any moment by throwing the clutch out of gear with the pinion I or wheel K.

During the regular operation of the machine, the clutch is operated automatically by the mechanism now to be described. On the crank-shaft U (figs. 1 and 3,) is a disk, V, from the periphery of which projects a pin, m, which, as the disk revolves, engages alternately with the cams n and p on rock-shaft S', and imparts a rocking motion to that shaft. At one end of that shaft projects an arm, carrying a weight, W', which gives momentum to the movements of the shaft, and causes it to obey promptly and energetically the impulse of the pin m, imparted to the cams n p. On the opposite end of shaft S' is an arm, a', having a fork in its extremity, which engages pin f on slide M. By reason of this connection the oscillation of shaft S' imparts a reciprocating movement to slide M, and causes the clutch L to engage alternately with pinion I and gear-wheel K, during each revolution of shaft U. Pinion I gears into the large gear-wheel W on shaft U, and wheel K gears into wheel T, of equal size with itself, on shaft U. When pinion I is clutched to shaft H, it drives wheel W and its shaft U, at a speed much slower than its own, owing to the relative sizes of the wheel and pinion; but when wheel K is clutched to shaft H, it becomes the driving-wheel, and, by means of wheel T, drives shaft U at a much greater speed than it received from pinion I and wheel W. The slow movement of shaft U is intended to be applied during that portion of its revolution which effects the descent of the knife, and the more rapid movement during that portion which raises the knife for a repetition of the cut. On the forward end of shaft U is crank X (figs. 1 and 3,) connected by pitman Y with the knife-stock Z, which is hung on parallel rods, A', and swings between suitable guides on the frame. The knife k is attached to its lower edge. Thus the

operation of the knife is effected by the rotation of the crank-shaft U. C' is a sliding clamp operated by the wheel D' in the usual manner, to hold the paper firmly while under the operation of the knife. G' is a sliding gauge, which is moved backwards and forwards on the table T' by means of a screw, q, which runs through an arm of G'; projecting downward through a slot, v, in the table. This screw is operated by the wheel H', and draws the gauge to or from the knife k. Attached to the arm of gauge G', under the table, is a rod, r, having an index, t, which slides along a graduated scale, s, as the gauge is moved back and forth. By means of wheel H', and the scale and index, the position of the gauge can be adjusted with perfect accuracy.

The operation of the machine is as follows: The knife being down in contact with the table, and motion being given to the main shaft E in any suitable manner, the operator, by means of the hand-lever N, throws the clutch L into gear with wheel K, which, in the manner before explained, imparts rapid revolution to shaft U, and raises the knife k quickly to the top of its stroke. At that point the arm a' of shaft S' is moved by the action of the appropriate cam, so as to throw the clutch L into gear with pinion I, which, as before explained, imparts a slow movement to shaft U, and brings the knife, by a slow "draw" cut, down upon the table, severing any paper that may be placed under it, along a line determined by the previous adjustment of the gauge. The arm a' again shifts the slide M, so as to throw clutch L into gear with wheel K, and raises the knife by a quick motion to the top of its stroke, ready for a repetition of the operation. The operation can be arrested at any time, by means of the treadle S or hand-lever N.

Having thus fully described my invention, what I claim, and desire to secure by Letters Patent, is—

1. Operating the knife by connecting it with the crank X, in the manner described.
2. In a paper-cutting machine, the combination, with the gauge, of rod r, index t, and graduated scale s, in the manner and for the purpose set forth.
3. The arrangement of gearing herein described, for regulating the speed of the knife, giving it a slow movement on its downward stroke, and a quick movement on its upward stroke, as set forth.

The above specification of my said invention signed and witnessed at Boston, this 18th day of September, A. D. 1867.

GEORGE H. SANBORN.
